UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

RADIANT HEAT SUPERHEATER

Application filed December 5, 1928. Serial No. 323,892.

This invention relates to a novel form of radiant heat superheater. In the annexed drawings, in which I have shown one embodiment of the invention,

5 Fig. 1 is a sectional view through a portion of a furnace having the invention applied thereto.

Fig. 2 is a section on the line 2—2 of Fig. 1.

10 Fig. 3 is a section taken on the line 3—3 of Figs. 1 and 4.

Fig. 4 is a view taken on the line 4—4 of Fig. 3.

15 Fig. 5 is a longitudinal sectional view through one of the tubes forming part of the superheater.

Fig. 6 is a section on the line 6—6 of Fig. 5.

I have shown the invention as embodied 20 in a boiler having water tubes 1 of any usual form and arrangement, these tubes being shown as disposed above a combustion chamber 2 of a furnace having a chain-grate stoker 3. The radiant heat of the combustion 25 chamber is used to heat steam in a radiant heat superheater comprising two rows of tubes 4 and 5, the tubes 4 being disposed inwardly from the tubes 5. By the terms "inwardly" and "outwardly", I refer to the 30 relative positions of elements with respect to the combustion chamber.

The superheater also includes a header 6 which is common to the tubes in both rows, and it also includes an inlet header 7 and an 35 outlet header 8. The inlet header is connected by a pipe 9 to the usual steam space of the boiler, not shown. The outlet header 8 is connected in the usual manner to the main steam line.

40 The tubes 4 are preferably spaced apart, as shown, so as to permit some of the radiant heat to pass therebetween to the tubes 5. At the same time the tubes 4 act as a shield for the tubes 5, thus protecting them against

45 the intense heat of the combustion chamber. The tubes 4 are preferably provided with a protective coating, the tubes themselves being metallic and the covering 10 being of relatively refractory material, by which term I

50 mean a material which is relatively non-

conductive of heat as compared with metal. Suitable projections 11 on the tubes serve to hold the covering in place.

The outer tubes 5 may be of the rectangular form shown, thus presenting flat faces to the combustion chamber, and when the tubes are placed in a row, these flat faces will consequently present a substantially continuous metallic surface to the heat reaching them.

It is of course understood that the tubes 5 are preferably made of the usual metallic form. The space between the tubes 5 may be sealed with refractory material, as shown in the drawings, or the tubes may be made to come close enough together to make it unnecessary to use any material between them.

55 60 65 65 Operating conditions will govern the character of the material used in the spacers.

The tubes 5 are preferably supported in such a manner as to permit expansion and contraction both lengthwise and transversely.

To accomplish this purpose I have shown them supported by a device which is more fully described and claimed in my copending application, Serial No. 371,910. This device

70 75 80 80 comprises a plurality of plates 13, each of which has a plurality of tubes 5 welded thereto, as indicated at 14 in Fig. 3. Each of these plates is provided with a longitudinally ex-

tending slot 15 in which is received a bolt 16 passing through a supporting beam 17. This beam at its ends is provided with holes

85 85 85 through which pass bolts 18 which are received in spaced ears 19 secured in the walls 20 of the furnace. At one end of the beam

the ears 19 are provided with slots 21 whereby the entire beam may be moved transversely of the length of the tubes to permit expansion in this direction. The bolts 18 loosely engage

90 the beam 17, whereby longitudinal movement of the tubes is permitted.

In operation, steam is preferably introduced into the superheater in the manner shown in Fig. 1, that is, downwardly through the inner tubes 4. It then may be permitted

95 to pass upwardly through the tubes 5. By this arrangement the relatively cool steam is introduced to the tubes which form a shield for the other tubes, and which are consequently exposed to the more intense heat.

I claim:—

1. In a radiant heat superheater, two rows of tubes, one disposed inwardly from the other, the tubes of the outward row having their inner faces substantially flat and forming a substantially continuous surface across the row, and the tubes of the inner row being spaced apart to permit passage of radiant heat to said flat faces of the outer row, and 10 means causing steam to flow through first one row and then the other.

2. In a radiant heat superheater, a furnace, two rows of tubes extending along one side of the path of the general gas flow in the furnace, 15 one disposed inwardly from the other, the tubes of the outer row being placed relatively close together, and the tubes of the inner row being differently spaced apart and offset relative to the tubes of the first group to permit 20 heat to pass therebetween to the outer row, and means causing steam to flow through first one row and then the other.

3. In a radiant heat superheater, two rows of tubes, one disposed inwardly from the 25 other, the tubes of the outer row being placed relatively close together, the tubes of the inner row being spaced apart to permit heat to pass therebetween to the outer row, the tubes in the outer row being substantially rectangular 30 and those in the inner row being substantially cylindrical, and means causing steam to flow through first one row and then the other.

4. In a radiant heat superheater, two rows of tubes, one disposed inwardly from the 35 other, the tubes of the outer row being placed relatively close together, the tubes of the inner row being spaced apart to permit heat to pass therebetween to the outer row, those in the outer row having metallic faces on the inner 40 sides thereof, and those in the inner row being at least partially formed of relatively refractory material, and means causing steam to flow through first one row and then the other.

5. In a radiant heat superheater, two rows of tubes, one disposed inwardly from the other, means protecting the tubes of the inner row from the heat to which they are exposed, support for the tubes of the outer row, an 45 expansible connection between said support and tubes, and means causing steam to flow through first one row and then the other.

6. In a radiant heat superheater, two rows of tubes, one disposed inwardly from the other, means protecting the tubes of the inner 55 row from the heat to which they are exposed, support for the tubes of the outer row and an expansible connection between said support and tubes permitting expansion of the tubes both longitudinally and transversely.

60 7. In a radiant superheater comprising, a combustion chamber, a row of spaced tubes extending through a portion of the chamber and constituting the first steam pass of a multiple steam pass superheater, a second 65 row of tubes subject to less intense radiant

heat and delineating a gas confining furnace wall spaced from the first row of tubes, and means connecting the rows of tubes to cause steam to flow from the first tubes into the second in a series flow.

8. In a steam boiler installation, a combustion chamber, a bank of steam generating tubes above the combustion chamber, a superheater outlet header outside the combustion chamber, an intermediate superheater header outside the combustion chamber, a bank of bowed superheater tubes exposed to radiant heat from the combustion chamber and extending through a wall of the chamber, connections between the inlet ends of said tubes and the intermediate header, connections between the discharge ends of the tubes and the outlet header, a superheater inlet header outside the combustion chamber, and a row of bowed superheater tubes extending from the inlet header through the same chamber wall to the intermediate header and disposed inwardly of the combustion chamber with reference to the first row of tubes, the first and second rows of tubes being of approximately the same length in the chamber.

HOWARD J. KERR.
